UNITED STATES PATENT OFFICE.

FREDERICK C. ROBERTS, OF MOHAWK, NEW YORK, ASSIGNOR OF ONE-HALF TO DANIEL P. VAN COURT, OF SAME PLACE.

STEAM-ENGINE.

SPECIFICATION forming part of Letters Patent No. 364,374, dated June 7, 1887.

Application filed January 17, 1887. Serial No. 224,579. (No model.)

To all whom it may concern:

Be it known that I, FREDERICK C. ROBERTS, of Mohawk, in the county of Herkimer, in the State of New York, have invented new and useful Improvements in Steam-Engines, of which the following, taken in connection with the accompanying drawings, is a full, clear, and exact description.

This invention consists in a novel construction of a steam-engine in which the friction of the piston is reduced to a minimum and the steam-pressure is applied to the piston in the most advantageous manner, all as hereinafter more fully described, and specifically set forth in the claims.

The invention is fully illustrated in the annexed drawings, wherein Figure 1 is a side elevation of a steam-engine embodying my invention. Fig. 2 is an enlarged face view of the side of the cylinder to which the steam-chest is attached, the cover of the latter being removed to show the interior of the steam-chest; and Fig. 3 is a transverse section of the steam-cylinder with the steam-chests attached thereto.

Similar letters of reference indicate corresponding parts.

A represents the steam-cylinder, which I divide into longitudinal compartments A' A', of equal dimensions, by hollow longitudinal partitions P P, of sectoral form, in cross-section.

C C are oscillatory pistons, preferably formed in one piece, to insure their operation in unison, and also to reduce the cost of manufacture. These pistons consist of plates extending the length and width of the compartments A' A', and fitted with their edges steam-tight to said compartments. They are pivoted in the axis of the cylinder A, and are formed with a cylindrical enlargement, a, along their axial portion. In order to fit the said pistons steam-tight to the partitions P P, I provide the latter with longitudinal grooves b, adjacent to the axial enlargement a of the pistons, and in said grooves I place adjustably the anti-friction metal packing strips or gibs c, which I bring to bear on the portion a of the joined pistons by means of set-screws d d, introduced into the hollow partition, and inserted in screw-threaded holes extending from the cavities of the partitions to the grooves b,

as shown in Fig. 3 of the drawings. The edges of the pistons I provide with longitudinal grooves, in which I secure anti-friction metal packing strips or facings e, by which the pistons are fitted steam-tight to the compartments 55 A' A'.

f f denote steam-ports extending through the sides of the cylinder at opposite sides of the respective partitions P P, and h h denote exhaust-ports in the outer portions of the aforesaid partitions, between the steam-ports. The exterior of the cylinder A is formed with valve-seats e' e', at the sides through which the aforesaid ports are extended, and upon said valve-seats are placed the valves D D, 60 65 70 75 80 85 90 95 100

closed in the steam-chests F F. Said valves may be of any suitable and well-known form. The form here illustrated for exemplification merely is that of an ordinary slide-valve. The two valves D D are reciprocated alternately in opposite directions from each other, and as one valve admits live steam to one compartment A', at one side, the other valve allows the steam to exhaust from said compartment, at the opposite side, and thus the intervening piston C is forced from one side of the compartment to the opposite side thereof; and inasmuch as the ingress and egress of steam of the two compartments is reverse and the two pistons are united, they are compelled to operate in unison and with double force.

The described duplex piston is provided at opposite ends with trunnions, one or both of which project through stuffing-boxes n on the exterior of the cylinder, and to the protruding ends of said trunnion is attached a crank, L, from which motion is transmitted to the main driving-shaft o by a shorter crank, u, attached to said shaft, and connected with the crank L by the connecting-rod N, as represented in Fig. 1 of the drawings. To the driving-shaft is also attached the eccentric u, from which to transmit motion to the valves D D. The means for transmitting this motion may be varied, and can be devised by any engineer of ordinary skill.

For exemplification, I have shown a bell-crank, p, one arm of which is connected with the eccentric-rod r, and the other arm is connected by a rod, s, with a walking-beam, H, the two

ends of which are connected, respectively, with the rods or stems of the valves D D by intermediate links, *i. e.* l l represent the steam-pipes, which conduct the steam from the boiler 5 to the steam-chests, and t t denote the exhaust-pipes.

Having described my invention, what I claim as new, and desire to secure by Letters Patent, is—

- 10 1. A steam-engine comprising a steam-cylinder having at diametrically-opposite sides sectoral longitudinal partitions, steam-ports through the side of the cylinder at opposite sides of each of said partitions, exhaust-ports 15 in the partitions, steam-chests and valves on the exterior of the cylinder and respectively over the aforesaid ports, oscillatory pistons formed in one piece, with a cylindrical enlargement along the axial portion pivoted in 20 the axis of the cylinder and extending the length and width of the compartments of the cylinder, and adjustable bearings between the axial portion of the piston and the adjacent portion of the partitions, as set forth and shown.

2. The combination of the steam-cylinder divided into compartments by hollow longitudinal partitions, oscillatory pistons formed in one piece with a cylindrical enlargement along the axial portion and pivoted in the axis of the cylinder, gibs adjustably connected to the partitions adjacent to the axial portions of the pistons, set-screws extending from the cavities of the hollow partitions to the gibs for adjusting the same, and anti-friction facings secured to the pistons along the edges thereof, substantially as described and shown. 25

In testimony whereof I have hereunto signed my name and affixed my seal, in the presence of two attesting witnesses, at Mohawk, in the county of Herkimer, in the State of New York, 40 this 23d day of December, 1886.

FREDERICK C. ROBERTS. [t. s.]
